WOVEN ECCLESIASTICAL BANDING

Arthur J. Vervaet, Paterson, N. J.

Application May 6, 1952, Serial No. 19,601

Term of patent 7 years

(Cl. D3—9)

To all whom it may concern:

Be it known that Arthur J. Vervaet, a citizen of the United States, residing at 109 Montgomery Place, Paterson, in the county of Passaic and State of New Jersey, has invented a new, original, and ornamental Design for Woven Ecclesiastical Banding, of which the following is a specification, reference being had to the accompanying drawing, forming part thereof.

The figure of the drawing is a plan view of a piece of woven ecclesiastical banding showing my new design.

I claim:

The ornamental design for a woven ecclesiastical banding, substantially as shown.

ARTHUR J. VERVAET.
